UNITED STATES PATENT OFFICE

102,423

DESIGN FOR A GAME APPARATUS

Paul M. Fuller, Chicago, Ill., assignor to The Rudolph Wurlitzer Company, North Tonawanda, N. Y., a corporation of Ohio

Application October 19, 1936, Serial No. 65,356

Term of patent 7 years

To all whom it may concern:

Be it known that I, Paul M. Fuller, a citizen of the United States, residing at Chicago, in the county of Cook and State of Illinois, have invented a new, original, and ornamental Design for a Game Apparatus, of which the following is a specification, reference being had to the accompanying drawing, forming a part thereof.

The figure is a perspective view of the game apparatus embodying my design.

I claim:

The ornamental design for a game apparatus, substantially as shown.

PAUL M. FULLER.
